(57) **CLAIM**

The ornamental design for a compost bin, as shown, and described.

DESCRIPTION

FIG. 1 is a perspective view of a compost bin;

FIG. 2 is a front view thereof;

FIG. 3 is a rear view thereof;

FIG. 4 is a left elevation view thereof, the right elevation view being a mirror image thereof;

FIG. 5 is a top plan view thereof; and,

FIG. 6 is a bottom plan view thereof.

The broken lines in the drawings depict portions of the compost bin that form no part of the claimed design.
